UNITED STATES PATENT OFFICE.

EUGENE A. JONES, OF LOS ANGELES, CALIFORNIA.

SPARK-PLUG TERMINAL.

1,382,090.

Specification of Letters Patent. Patented June 21, 1921.

Application filed January 6, 1920. Serial No. 349,322.

To all whom it may concern:

Be it known that I, EUGENE A. JONES, a citizen of the United States, residing at Los Angeles, in the county of Los Angeles and 5 State of California, have invented a new and useful Improvement Comprising a Spark-Plug Terminal, of which the following is a specification.

My invention relates to internal combustion engines, and more especially to the ignition of such engines. It is at the present time standard practice in the art to provide spark plugs which are usually formed of porcelain and which pass through the head 15 of the cylinder into the explosion space, these spark plugs carrying a spark gap at the inner end and being connected to some source of high tension electricity which is caused to discharge through the spark plug 20 and across the spark gap at the instant that the explosion is desired. It is a well known fact that the efficiency of the spark gap inside the engine can be increased if another spark gap is placed in series with it, and 25 many devices have been made for this purpose.

In my invention I provide a plurality of spark gaps for each spark plug outside the engine, these spark gaps being arranged 30 in multiple with each other and in series with the spark gap inside the engine. I am unable to explain the electrical theory of my invention, but I know from practical experiments that a much "fatter" and larger spark 35 is obtained at the spark gap inside the engine with my device in place than is possible where my invention is not used.

Referring to the drawing which is for illustrative purposes only,

40 Figure 1 is a side elevation of a part of an engine with the spark plug in place therein.

Fig. 2 is an enlarged view of the upper portion of the spark plug.

Fig. 3 is a plan view of the same with the 45 clamping nut removed.

In the form of my invention illustrated in these drawings, the engine is shown at 11 having a spark plug 12; this spark plug is fed with high tension current through a 50 high tension cable 13 from suitable standard ignition apparatus, not shown. Secured to the end of the cable 13 is a terminal 14 which is preferably formed of copper or brass sheet which is flattened out to form an eye and 55 provided with a hole 16 which is somewhat larger than the connection stud 17 of the

spark plug 12. The eye 15 of the terminal 14 is embedded in insulating material 20. This insulating material may be hard rubber or any substance which is an insulator and 60 which can be molded around the eye 15. The terminal 14 with the insulation 20 in place is slipped over the connection stud 17, a hole being left in the center of the insulation 20 somewhat larger than the stud 17, 65 and the terminal with its insulation is clamped in place between a fixed nut 21 and a nut 22 threaded on the stud 17. The insulation 20 is so disposed that the eye 15 does not come into direct metallic contact 70 with the stud 17 or the nuts 21 and 22. In molding the insulation 20 about the eye 15, however, four cavities 30 are formed in the top of the insulation the eye 15 being exposed through these openings. When the 75 nut 22 is screwed in place four spark gaps are formed between the bottom of the nut 22 and the top of the eye 15 through the cavities 30. It is obvious that these cavities might be formed between the eye 15 and the 80 nut 21, if desired. Upon supplying the high tension current through the cable 13 it must jump across the gap in the cavity 30 and then through the stud 17 and the spark gap on the inner end of the spark plug 12 in the 85 standard manner. It should be noted that the cavities 30 are entirely inclosed on all sides when the nut 22 is screwed down so that the air is excluded therefrom and so that there is no danger of the spark igniting 90 any gasoline vapor which may be floating inside the engine hood.

I claim as my invention:

1. In an internal combustion engine, a spark plug having a connection stud in the 95 top thereof; a high tension terminal; insulation interlocked with said terminal and having an opening through which said stud passes without electrical contact with said terminal; and a nut threaded on said stud 100 and clamping said insulation to the top of said spark plug, said insulation being cut away to form a spark gap over which electrical discharges may pass from said terminal to said stud.

2. In an internal combustion engine, a spark plug having a connection stud in the top thereof; a high tension terminal; insulation between said terminal and said nut having an opening through which said stud 110 passes without electrical contact with said terminal; and a nut threaded on said stud

and clamping said insulation to the top of said spark plug, said insulation being cut away to form a spark gap over which electrical discharges may pass from said terminal to said stud.

3. In an internal combustion engine, a spark plug having a connection stud in the top thereof; a high tension terminal; insulation between said terminal and said nut having an opening through which said stud

passes without electrical contact with said terminal; and a nut threaded on said stud and clamping said insulation to the top of said spark plug, said insulation being cut away to form a spark gap in which a portion 15 of said terminal is embedded.

In testimony whereof, I have hereunto set my hand at Los Angeles, California, this 30th day of December, 1919.

ENGENE A. JONES.
